SPOON OR SIMILAR ARTICLE

Ellen Manderfield, Syracuse, N.Y., assignor to Oneida Ltd., Oneida, N.Y., a corporation of New York

Filed July 7, 1961, Ser. No. 65,836

Term of patent 14 years

(Cl. D54—12)

FIG. 1

FIG. 1 is a front elevational view of a spoon, showing my new design;

FIG. 2 is a back elevational view of the spoon;

FIG. 3 is a side elevational view of the spoon; and

FIGS. 4 and 5 are sections on the respective lines 4—4 and 5—5 of FIG. 1.

The essential features of my design for a spoon or similar article reside in the configuration of the handle in combination with the particular type of ornamentation as applied thereto.

I claim:

The ornamental design for a spoon or similar article, substantially as shown and described.
